MOP

Filed March 17, 1928

Inventor

Theodore A. Morris

By Mason Fenwick Lawrence
Attorney

UNITED STATES PATENT OFFICE.

THEODORE A. MORRIS, OF BOSTON, MASSACHUSETTS.

MOP.

Application filed March 17, 1928. Serial No. 262,362.

This invention relates to improvements in mops used in scrubbing, brushing, and polishing floors or other similar surfaces.

An object of this invention is to provide an improved clamping means for detachably connecting the mop strands to the handle.

A further object of this invention is to provide a clamping means for the mop strands which may be easily attached to the handle in such a manner that the mop liquid will not seep into the upper clamped edges of the strands, the lower end of the handle cooperating with the upper folded edges of the strands for eliminating the possibility of dirt being received therebetween.

A further object of this invention is to provide a clamping means for firmly holding the folded edges of a plurality of mop strands in operative position, in such a manner that the possibility of the mop liquid being absorbed through the clamped edges is practically eliminated.

Other objects of this invention will appear from the following detailed description of the device, and as disclosed in the single sheet of drawings which is herewith made a part of this application.

In the drawings:

Fig. 1 illustrates a perspective view of the mop, disclosing the strands and clamping members in assembled and interlocked relationship with the handle.

Fig. 2 represents to an enlarged scale a side elevational view of a clamping member in interlocked relationship with the upper folded edges of the mop strands and the lower end of the handle.

Fig. 3 illustrates an end elevational view of Figure 2.

Fig. 4 represents to an enlarged scale sectional view of Figure 2 taken along line 4—4.

Fig. 5 illustrates a sectional view of Figure 2 taken along line 5—5.

Fig. 6 represents a perspective view of one of the clamping members.

The improved mop according to this invention consists primarily of a plurality of mop strands 1, made of any suitable material, such as hemp, or otherwise, the strands being folded in a series along an edge 2, and held firmly together in reinforced relationship by means of a binding 3, made of any suitable material, such as a fabric, and adapted to be securely sewed, or otherwise, to the strand mem-

bers 1, along a line spaced a suitable distance from the folded edge 2 of the strand members 1, as clearly disclosed at 4, which shows the upper edge of the fabric reinforcing element 3, spaced from the folded edges 2 of the strand members, while numeral 5 designates the lower edge of the reinforcing member 3.

For the purpose of firmly and detachably clamping the mop strands 1 into interlocked relationship with a handle 6, it is preferred in this invention to provide a plurality of clamping members having upwardly extending shank portions 7 and 8, for receiving the handle 6, and portions 9 and 10, extending at right angles thereto for receiving the mop strands.

The means for bringing clamping portions 9 and 10 under tension for holding the folded edges 2 of the strands 1 in position therebetween, may be of any suitable type, but it is preferred in this invention that a plurality of openings be formed in the reinforcing element 3, as disclosed at 11, 12, and 13, the openings to extend through the binding member 3, and the strand members 1, in such a manner that sleeve members 14, 15, and 16, made of any suitable material, may be inserted therein and held firmly in position by means of outwardly extending flanged portions 17, 18, 19, 20, 21 and 22, the sleeve members being of such a length that the flanged portions thereon will just fail to come in contact with the clamping portions 9 and 10, when the strand members are under tension therebetween.

As one means for bringing the clamping portions 9 and 10 under tension, it is preferred that tension bolts 23, 24, and 25 be provided having shank portions 26, 27, and 28, supplied with suitable threaded portions 29, for receiving a cooperating threaded shank portion 30.

Suitable washers 31 and 32 are provided to cooperate with the tension bolts and clamping members in such a manner that they will aid materially in maintaining a non-leakable condition in the clamped members.

As an additional means of firmly holding the folded edges 2 of the strand members 1, in clamped relationship between the portions 9 and 10, it is preferred that inwardly extending indentations 33 and 34 be formed approximately below the shank portions 7 and 8 of the clamping members in such a manner that they will tend to project inwardly against the folded edges of the strand mem-

bers when they are brought under tension, as clearly disclosed in Figure 4, and therefore aid materially in securely holding the strands in position.

5 The lower longitudinal edges of the portions 9 and 10, of the clamping members are provided with inwardly extending flanged portions 35 and 36, for the purpose of securely gripping the strands 1 along a line approximately coincident with the lower peripheral edge 5 of the binding member 3, as clearly disclosed in Figure 4.

10 The lower end of the handle 6 is adapted to be clamped into position between the shank portions 7 and 8 of the clamping members by any suitable means, such as that shown in Figure 4, wherein an opening 37 is formed in the handle through which is adapted to extend a tension bolt 38, similar to the tension bolt used in connection with the cooperating clamping portions 9 and 10, or otherwise, as may be desired.

15 The inner end of the handle 6 is formed of a shape approximately shown in Figure 25 4, for the purpose of aiding in holding the folded edges 2 of the strands in position, and at the same time eliminates the possibility of dirt and other undesired elements from accumulating between the folded edges of the 30 mop strands and the lower end of the handle. For the reasons just described, the lower end of the handle 6, is formed approximately as disclosed at 39.

20 In order to maintain the folded edges 2 of the strands 1 in proper relationship to each other, and also make it practically impossible for them to be detached from the main body portion of the mop, a member 40 extends a suitable distance above the tension bolts 23, 25 and 24, and 25, and within the folded strand members 2.

25 This invention provides a mop constructed of comparatively few and simple parts, yet having an efficient clamping means for firmly 45 and detachably holding the mop strand members and a handle portion together, in such a manner that the device will be sanitary and

useful for a long period of time, each part being easily detached and reassembled as may be desired.

50

What I claim is:

1. In a device of the character described, a plurality of strands of mop material, a binding member securely fastened to the strands for holding them in constricted and folded relationship, a mop handle, a pair of clamping elements having upper portions for receiving the handle and the lower edged portions constructed with inwardly extending flanges receiving the mop strands therebetween, sleeve elements extending through and securing the binding member and strands of less length than the width of the folded strands, a plurality of tension elements extending through the sleeve members and the clamping elements, and means for bringing the pair of clamping elements under tension 60 against the handle.

2. In a device of the character described, a plurality of strands of mop material, a binding member securely fastened to the strands for holding them in constricted and folded relationship, a mop handle, a pair of clamping elements having upper portions for receiving the handle and the lower edge portions constructed with inwardly extending flanges receiving the mop strands therebetween, sleeve elements extending through and securing the binding member and strands of less length than the width of the folded strands, a plurality of tension elements extending through the sleeve members and the clamping elements, means for bringing the pair of clamping elements under tension 70 against the handle, the inwardly extending flanges projecting at right angles to the clamping elements, and indentations in the clamping members for holding the folded edges in close relationship, the inner end of the handle being formed to snugly fit the 75 folded edge of the strands.

80 85 90

In testimony whereof I affix my signature.

THEODORE A. MORRIS.
